US00D638701S

(12) **United States Design Patent**
Shapiro et al.

(10) **Patent No.:** US D638,701 S
(45) **Date of Patent:** ** May 31, 2011

(54) **CONTAINER**

(75) Inventors: **Catherine M. Shapiro**, Omaha, NE (US); **Jess C. Sweeney**, Omaha, NE (US); **Brian M. Degner**, Omaha, NE (US); **Darin Charles Koestring**, Evansville, IN (US); **Todd Preston Yunker**, Evansville, IN (US); **Kenneth Paul Meissbach**, Lawrence, KS (US)

(73) Assignee: **ConAgra Foods RDM, Inc.**, Omaha, NE (US)

(**) Term: **14 Years**

(21) Appl. No.: **29/369,419**

(22) Filed: **Sep. 8, 2010**

(51) LOC (9) Cl. **09-03**

(52) U.S. Cl. **D9/428**

(58) Field of Classification Search ..... D9/414–416, D9/418–420, 423–428, 430–432, 434, 435; D7/354, 392.1, 394, 396.1, 538, 543–545, D7/550.1, 551, 554.3, 587, 566, 575, 584, D7/586, 629, 667; 220/4.22–4.24, 574, 604–608, 220/659, 675, 781–782, 793, 835, 839, DIG. 14; 206/119, 470, 508, 545, 806; 229/406; 219/725, 219/735; D23/359; D3/302, 314

See application file for complete search history.

(57) **CLAIM**

The ornamental design for a container, as shown and described.

DESCRIPTION

FIG. 1 is a perspective view of a first embodiment of a container showing our new design;
FIG. 2 is a top plan view thereof;
FIG. 3 is a bottom plan view thereof;
FIG. 4 is a left elevation view thereof;
FIG. 5 is a right elevation view thereof;
FIG. 6 is a back elevation view thereof;
FIG. 7 is a front elevation view thereof;
FIG. 8 is a perspective view of a second embodiment of a container showing our new design;
FIG. 9 is a top plan view thereof;
FIG. 10 is a bottom plan view thereof;
FIG. 11 is a left elevation view thereof;
FIG. 12 is a right elevation view thereof;
FIG. 13 is a back elevation view thereof; and,
FIG. 14 is a front elevation view thereof.
The broken line portion of the container in the figure drawings is included to show unclaimed subject matter only and forms no part of the claimed design.

1 Claim, 10 Drawing Sheets
